LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

FRONT-HEAD CONSTRUCTION FOR SELF-ROTATING HAMMER-DRILLS.

1,130,957.

Specification of Letters Patent.

Patented Mar. 9, 1915.

Application filed February 5, 1914, Serial No. 816,814. Renewed January 4, 1915. Serial No. 509.

To all whom it may concern:

Be it known that I, LEWIS C. BAYLES, a citizen of the United States, residing at Easton, in the county of Northampton and 5 State of Pennsylvania, have invented a certain new and useful Improvement in Front-Head Construction for Self-Rotating Hammer-Drills, of which the following is a specification.

10 This invention relates to self-rotating hammer drills and more particularly to a front head construction for drills of this type for use in stoping or other drilling where it is necessary to drill vertical holes 15 in the roof of a stope or entry.

The object of this invention is to provide 20 a front head construction for drills of this type which will prevent dust from the hole from penetrating into the working parts of 25 the drill when it is used in vertical or nearly vertical drilling. With this object in view a front head construction has been devised, a practical embodiment of which is shown in the accompanying drawings in which—

25 Figure 1 shows a longitudinal section of a drill partly in elevation and Fig. 2 shows a transverse section taken on the line 2—2 of Fig. 1.

In the drawings, the invention is shown 30 applied to a stoping drill provided with an air feed of ordinary construction, the details of which form no part of the present invention.

As shown, the drill comprises a head block 35 1 to one side of which is secured an air feed 2 and to the other side of which is secured a drill cylinder 3 in which reciprocates a piston 4, the movement of which is governed by any desired form of valve 40 mechanism (not shown). The piston is given a step by step rotation by means of a fluted rifle bar 5 provided with the ordinary ratchet mechanism 6, this rifle bar 5 sliding in a bore 7 in the head of the piston provided with grooves which are engaged by the flutes on the rifle bar 5. On the forward side of the piston is a hammer bar extension 8 which is provided with straight flutes 9. Fitting into the forward end of the cylinder 3 is a cylinder head 10. In the rearward side of the cylinder head 10 is a bore 11 through which the hammer bar extension 8 projects. Forward of this is a larger bore 12 and forward of this second bore is a 55 third bore 13 of still larger diameter. For-

ward of the cylinder head 10 is a front head 14 which is secured by bolts 15 passing through lugs 16 to the cylinder 3 which is also provided with lugs 17 through which the bolts 15 pass. Springs 18 are provided between the heads of the bolts 15 and the lugs 16 to cushion the blow of the piston 4 on the cylinder head when the drill is not against the work. The front head 14 has an interior bore of the same diameter as the second bore 12 of the cylinder head. Rotatably mounted in the front head 14 is a shank portion 19 of a drill chuck 20. The rear end of this shank portion extends back and fits into the bore 12 and has an annular depression 21 in its outer surface which registers with the bore 13. In the annular chamber formed by this depression 21 and the bore 13 is a split retaining ring 22 which engages the rear edge of the front head 14 and prevents longitudinal movement of the drill chuck 20. These parts are assembled in the following manner: The shank portion 19 is slid into position within the front head 14 and the split ring 22 placed in the depression 21. These parts are then slid into place in the cylinder head 10 and secured together by means of the bolts 15. The shank portion 19 of the drill chuck is bored out to receive the hammer bar extension of the piston and is provided on its inner surface with grooves engaging the straight flutes 9 of the hammer bar extension. The drill chuck 20 is provided with a head portion 23 of larger diameter, the rear face of which overlaps the front end of the front head 14 and prevents any dust falling on the front end of the drill from entering the drill cylinder at the joint between these parts. The head portion of the chuck is bored out from its front end to receive the head portion 24 of a tappet 25 the shank 26 of which projects through a smaller bore into the interior of the shank portion 19 of the chuck so that it is struck by the hammer bar extension 8 of the piston 4. Threaded into the forward end of the head portion 23 of the chuck is a nose piece 27 through which is an angular longitudinal aperture 28 for the reception of the drill steel (not shown) the rear end of which can thus be struck by the tappet 25. The thread of the nose piece 27 is arranged in the same direction as the spiral flutes on the rifle bar 5 so that the rotation of the piston tends to tighten the nose 110

piece in the head portion of the chuck. Rearwardly inclined passages 29 are provided through the head portion of the chuck from the tappet bore so that any dust penetrating into the bore along the shank of the drill steel can easily escape and not work into the cylinder.

- 5 The operation of the device can easily be seen from the drawings and description.
- 10 The rotary movement of the piston caused by the rifle bar 5 will be communicated to the drill chuck 20 by means of the straight flutes 9 on the hammer bar extension of the piston causing relative rotation between the head portion 23 and the front head 14. With drills of ordinary construction the dust falling from the hole works down into the moving parts of the drill quickly resulting in destructive wear of the drill. In the present form the joint between the chuck and front head is entirely covered by the overlapping rear end of the head portion of the chuck and by this means and also by the rearwardly inclined passages from the tappet bore, dust is entirely prevented from entering the cylinder and affecting the moving parts.

Although the chuck is here shown rotated by the rotary movement of the piston communicated to the chuck by the fluted forward extension of the piston, it is obvious that other means might be employed without invention for directly or indirectly rotating the chuck and it is to be understood that the present showing and description discloses only one specified modification of my invention and other forms and modifications are included in the spirit and scope of the invention as expressed in the claims.

40 What I claim is:

1. In a fluid operated percussive drill, a cylinder, a front head secured to said cylinder, a drill steel receiving chuck having a shank portion rotatably mounted in said front head and a head portion of larger diameter overlapping the front end of said front head and having an angular steel receiving aperture therein, a split ring engaging said chuck shank and the rear end of said front head to prevent forward movement of said chuck and means for rotating said chuck.

2. In a fluid operated percussive drill, a cylinder, a self rotating piston having a forward extension, a front head secured to said cylinder, a drill receiving chuck having a rearward portion rotating in said front head and slidably engaged by said piston extension, said chuck having a head portion of larger diameter overlapping the forward edge of said front head and having an angular drill receiving aperture, and a split ring engaging said chuck and the rear edge of said front head to prevent forward movement of said chuck.

3. In a fluid operated percussive drill, a cylinder, a front head therefor, a drill chuck rotatably mounted in said front head, said drill chuck having an enlarged head portion overlapping the front edge of said front head and a ring secured to its rear end engaging the rear edge of said front head to prevent longitudinal movement, means to secure said front head to said cylinder, and means to rotate said drill chuck.

4. In a fluid operated percussive drill, a cylinder, a front head therefor, a drill chuck rotatably mounted in said front head, said drill chuck having an enlarged head portion overlapping the front edge of said front head and a ring secured to its rear end engaging the rear edge of said front head to prevent longitudinal movement, means to secure said front head to said cylinder and a piston having a fluted extension engaging said drill chuck.

5. In a fluid operated percussive drill, a cylinder, a front head secured thereto, a drill chuck having a shank portion rotatably mounted in said front head, and a head portion overlapping the end of said front head, said head portion having a tappet receiving bore in its front end, a tappet in said bore having a shank projecting into said chuck shank portion, a nose piece secured in said bore to retain said tappet in position, said nose piece having an angular aperture therethrough for the reception of a drill steel, and a piston having a forward extension sliding in said chuck and adapted to strike said tappet.

6. In a fluid operated percussive drill, a cylinder, a piston therein having a forward extension, a cylinder head for said cylinder having a bore for the passage of said forward extension, a larger bore forward of said first bore and a third bore of greater diameter forward of said second bore, a front head forward of said cylinder head having a bore of the same diameter as said second cylinder head bore, a drill chuck having a shank portion fitting said front head bore and said second cylinder head bore and bored to receive said piston extension, said shank portion having a depression registering with said third cylinder head bore, a split ring seated in said depression and projecting into said third bore to engage the rear edge of said front head, a head portion on said chuck overlapping the front end of said front head and means for rotating said chuck.

7. In a fluid operated percussive drill, a cylinder, a piston therein having a fluted forward extension, means for rotating said piston, a cylinder head for said cylinder having a bore for the passage of said forward extension, a larger bore forward of said first bore and a third bore of greater diameter forward of said second bore, a

front head forward of said cylinder head having a bore of the same diameter as said second cylinder head bore, a drill chuck having a shank portion fitting said front head
5 bore and said second cylinder head bore and engaged by said piston extension, said shank portion having a depression registering with said third cylinder head bore, a split ring seated in said depression and projecting into
10 said third bore to engage the rear edge of

said front head, and a head portion on said chuck overlapping the front end of said front head.

In testimony whereof, I have hereunto set my hand.

LEWIS C. BAYLES.
